A. E. SANBORN

REVERSIBLE AND INTERCHANGEABLE STOCKING TOP

Filed Oct. 18, 1924

INVENTOR.

Albert E. Sanborn,
BY *Amel & Jones*
ATTORNEY.

UNITED STATES PATENT OFFICE.

ALBERT E. SANBORN, OF LACONIA, NEW HAMPSHIRE.

REVERSIBLE AND INTERCHANGEABLE STOCKING TOP.

Application filed October 18, 1924. Serial No. 744,373.

To all whom it may concern:

Be it known that I, ALBERT E. SANBORN, a citizen of the United States, residing at Laconia, in the county of Belknap and State of New Hampshire, have invented new and useful Improvements in Reversible and Interchangeable Stocking Tops, of which the following is a specification.

This invention relates to improvements in stocking tops of that type which are separate from and independent of the leg of a stocking, and particularly to a reversible and interchangeable top for golf stockings and other fancy or so-called sport hose.

One object of the invention is to provide a stocking top having a pair of display portions or sections of different patterns, colors or finishes, and adapted to be reversed so that either display portion or section may be exposed for use, enabling the wearer to make corresponding changes in the appearance of the top and the general appearance of the stocking.

A further object of the invention is to provide a reversible and interchangeable stocking top which may be used in connection with a full length stocking extending above the knee, thus securing comfort to the wearer and preventing exposure of the limb or undergarments in cold weather.

A still further object of the invention is to provide a stocking top of the character described which is adjustable up or down on the leg, so that the top may be positioned properly on the leg, so as to suit the length of the leg of the wearer and the length of the knickerbockers or short-length trousers employed, in order that a most dressy or ornamental effect may be obtained.

A still further object of the invention is to provide a stocking top composed of connected inner and outer reversible portions or sections and having a garter held between them and in position to be employed for supporting the stocking top in the use of the top with either of its sections exposed.

A still further object of the invention is to provide a stocking top which is adaptable for use with plain stockings to convert the same into sport hose, and which obviates the necessity of the wearer keeping a large number of sport stockings with fixed tops on hand for a change of style or pattern from day to day, the invention allowing the same advantage and effect to be secured by the use of less expensive stockings in connection

with tops capable of being interchangeably applied to vary the appearance of the stockings on different occasions as desired.

With these and other objects in view, the invention consists of the features of construction, combination and arrangement of parts, hereinafter fully described and claimed, reference being had to the accompanying drawing, in which:

Figure 1 is a view illustrating the application of my improved stocking top to a pair of hose, with one of the top sections exposed for use, a portion of the stocking top being broken away to show the interior construction.

Figure 2 is a side elevation of the stocking top as shown in Figure 1 removed from the stocking.

Figure 3 is a view, mainly in vertical section, of the stocking top as shown in Figures 1 and 2.

Figure 4 is a view similar to Figure 2 of the stocking top reversed to expose the other section thereof.

Figure 5 is a view similar to Figure 3 of the stocking top as shown in Figure 4.

Referring now more particularly to the drawing, 1 designates a stocking, of full length type in connection with which the invention may be used, said stocking having the top portion 2 to extend above the knee of the wearer.

The improved stocking top 3 embodying my invention comprises a band adapted to 90 embrace the leg and overlie the stocking 1, said band comprising two or more (at least two) tubular members, portions or sections, each knitted or otherwise suitably formed. In the present instance two such tubular 95 members or sections 4 and 5 are shown. One or the other of these sections is normally arranged within and enclosed by the other, said sections lying close to each other and in concentric relationship. Each section is provided with a selvaged upper edge and the selvaged upper edges of the two sections are united by sewing or otherwise 100 seaming them together at the bight or fold line 6, forming the turned upper edge of 105 the improved top.

Each section 4 and 5 is provided with a finished surface and an unfinished surface. The section 4, for example, is provided with a finished surface 7 and an unfinished surface 8, while the section 5 is provided with a finished surface 9 and an unfinished sur-

face 10. In other words, the section 4 is provided with an obverse display face 7 of a desired color, pattern or distinctive appearance, and the section 5 with an obverse display face 9 of a color, pattern or finish differing from or contrasting with that of the face 7 of the section 4. The inner or reverse sides 8 and 10 of these respective sections 4 and 5 are so arranged as to be 10 always concealed and may constitute the raw or unfinished sides of the respective patterns.

The unfinished surfaces 8 and 10 of the two sections 4 and 5 are arranged to face 15 each other, thus disposing the surfaces 7 and 9 to face in opposite directions. Thus it will be understood that when the finished side 7 of the section 4 is disposed on the outer side of the stocking top to form the 20 display face of said top, as shown in Figures 1, 2 and 3, the surface 9 of the section 5 will be disposed on the inner side of the complete top, and, when the top is reversed or turned inside out, as shown in Figures 4 25 and 5, the surface 9 of the section 5 will form the display surface of the top while the surface 8 of the section 4 will assume the inner position formerly assumed by the surface 10 of the section 5. It will be apparent 30 from this that when the surface 7 is exposed for use, a stocking top having a display face of a certain color or pattern will be presented, while, when the top is reversed to bring the surface 9 in position as the display face, a display surface of a contrasting color, pattern or finish from that of the face 35 7 will be presented. This change in the style or pattern and appearance of the stocking top is accomplished by simply turning 40 the same inside out from the condition shown in Figures 1, 2 and 3, or from that shown in Figures 4 and 5, providing a stocking top having two distinctive display surfaces, either of which may be disposed in position 45 for use.

The improved stocking top is designed to be used in connection with a full length stocking which may be drawn over the knee, for greater comfort in cold and inclement 50 weather, the top being disposed about the stocking so as to come below the knee in the manner in which ornamental stocking tops, like those of golf or sport hose, are commonly worn. This allows any type of plain 55 stocking to be worn in conjunction with an ornamental stocking top having two distinct pattern or style faces, either of which may be used as desired, with the result of not only presenting a different effect of stocking top but also changing the general appearance of the stocking. The stocking top is slidably adjustable on the leg, so that it 60 may be positioned different distances below the knee according to the length of the 65 knickerbockers or short trousers worn by the

user, allowing a proper finish at the edges of the trousers to be secured, impossible with stockings of the type having fixed ornamental stocking tops. Any suitable type of garter or support for holding the stocking 70 top in position may be employed. In the present instance I have shown the use of a preferred type, comprising an elastic garter band 11, held between the two top sections 4 and 5 adjacent to the bight or fold line 6, 75 and which by its elasticity holds the top in the desired position of adjustment, such garter band being, by its arrangement described, always disposed in position for use and so as not to interfere in any manner 80 with a reversal of the stocking top for the purposes described.

Figures 1, 2 and 3 show the stocking top as arranged to present the finished or patterned surface 7, which may be a distinctive 85 knitted pattern in plain or contrasting colors. The stocking may be worn with the stocking top in position to display the surface 7 on one day or on one occasion and then reversed by turning it inside out to present 90 the display surface 9, which may also be a knitted pattern in plain or contrasting colors. I do not limit myself, however, to the nature or character of the finished surfaces 95 of the sections 4 and 5, as such sections may be simply plain knitted in different colors to present display surfaces 7 and 9 of different solid colors, or they may be of different variegated colors, or they may be of different 100 figures or patterns, or a combination of any of these. The user may, by means of a single stocking top of the construction described use this stocking top in connection with a single pair of stockings or more than one pair of stockings to give the effect of 105 changed stockings with different stocking tops, and, by the use of two or more stocking tops of various styles, colors or patterns, may make as many changes as desired to give the effect of the possession of a number 110 of stockings differing in general appearance from each other and with a wide range of contrast in stocking top designs.

Stocking tops of this character may be made for the use of men, women and children for converting ordinary hose of suitable character into sport hose with fancy tops with economy in enabling the wearer to use plain hose which are less costly than sport hose with fixed fancy tops, and in enabling the wearer also to change the appearance of a single pair of hose at different times and on different occasions, avoiding the necessity of purchasing a plurality of pairs of hose for the purpose. The invention is also of advantage in enabling full length hose, which can be drawn over the knee, to be employed for greater comfort in cold or inclement weather and, particularly 120 in the case of children, where the knicker- 125

bockers terminate above the knee, to cover the bare flesh and prevent unsightly exposure of underwear. This advantage will also be one appreciated by golf players whose trousers are too short, and, in the event that the trousers are too long, a further advantage is gained in that the wearer may adjust the stocking tops on the legs to suit the length of the trousers and to give a proper finish at the trousers ends. By the use of a garter of the type shown and arranged within the stocking top as described, the necessity of employing cumbersome garters liable to tear the stockings or injure the flesh will also be avoided. Other advantages will be readily apparent to those versed in the art without a further and extended description.

Having thus fully described my invention, I claim:

A duplex stocking top formed separately

from a stocking and adjustable upwardly and downwardly thereon, said stocking top comprising two separately knitted tubular members seamed at their relatively upper edges to each other and lying one within the other and concentrically with relation to each other, each tubular member having a pattern side knit therewith and a raw or unfinished side, the pattern sides of the respective tubular members normally lying one on the outer face and the other on the inner face of the duplex top, and said pattern sides being of contrasting design and appearance, whereby one pattern side is normally displayed and by turning the duplex top inside out the positions of the pattern sides will be reversed for display of the other pattern side.

In testimony whereof I affix my signature.

ALBERT E. SANBORN.
